UNITED STATES PATENT OFFICE.

RALPH B. BIRD, OF OAKLAND, CALIFORNIA.

HAND ROLLER.

Application filed January 18, 1922. Serial No. 530,064.

To all whom it may concern:

Be it known that I, RALPH B. BIRD, a citizen of the United States, residing at 220 Lake Shore Boulevard, Oakland, in the county of Alameda and State of California, have invented certain new and useful Improvements in Hand Rollers, of which the following is a specification.

This invention relates to rollers, and in particular to pressure-rollers of that type by which the application of the pressure thereto, is by means of the hand.

The objects of the invention are, to produce a hand-roller of this type as a new article of manufacture, so designed and constructed as to be light in weight and yet give maximum service with minimum hand-pressure effort; to provide a handle of substantial form and grip and symmetrically positioned with respect to the device so as to eliminate the tiresome muscular strains of the wrist, so commonly encountered while using existing rollers; also to form the roller with tapering ends to eliminate the edge-lines of the roller on the article or surface rolled, and also to provide the device with ball bearings for ease of operation and minimum upkeep.

One of the major arts in which my invention may be employed is that of photography, for the purpose of rolling prints; that is, when the prints are removed from the bath they are laid upon a hard smooth special surface and judiciously rolled to remove the water and air bubbles therefrom. Prints rolled in this manner when removed from the hard surface have a high-grade uniform finish. There are many other efficient uses in other arts for my improved hand-roller, but as a concrete adaptation of it, the detailed description following will be with a print-roller in view.

The objects recited above and others are accomplished by the new and novel manner of construction and arrangements of parts shown in the accompanying drawing and set forth in the specification.

Referring to the said drawing, Fig. 1 represents a plan view of the hand-roller; Fig. 2 a side elevation of it with the roller and the extremity of one arm in section; Fig. 3 is an end elevation of the device, and Fig. 4 a view partly in section of a modified form of roller.

1 in Fig. 1 represents the center from which two pairs of arms 2, 2 and 3, 3 ra-

diate, forming a frame of spider-like construction. The arms 2, 2 lie in a plane and have their ends turned downwards, shown clearly in Fig. 2, terminating in bosses 4 for the support of a shaft 5. The arms 3, 3 lie also in a plane, which latter may be at right angles to the former plane; these arms are turned upwards, their extremities terminating in a cross-member 6, forming with said member a looped handle. The member 6 may be hollow and enlarged in the center gradually tapering towards its ends as shown, affording a strong substantial grip. The wide loop of the handle allows the fingers to pass through and be closed about the cross-member in any manner best suited to the operator.

The frame may be of unit construction, a single casting of aluminum or other preferred material. The frame carries the shaft 5 which may be a single rod or two shorter pieces, an end of each being supported in the bosses 4 by the screw 5' or any other well known manner.

7 is a roller rod-like in form, preferably made of hard wood and is carried by the shaft 5. The roller is formed with rounded tapering ends 8, to eliminate all edge-lines of the ends of the roller on the wet prints when rolling it over the prints on a hard surface. The roller may be covered by a rubber tube or sleeve 9, snugly fitting it and conforming to the longitudinal surface thereof. The roller may also be grooved as at 10, and the sleeve provided with a tongue to engage the groove to prevent lateral displacement of the sleeve in operation.

In Fig. 2 the end faces of the roller are shown recessed, engaging ordinary ball bearings 11 pressed or otherwise secured therein for the purpose of minimizing friction.

In the modification of the roller shown in Fig. 4, the longitudinal bore is of the same diameter as the counterbore of Fig. 2 for the ball bearings 11, and the latter bearings may be spaced apart by the tubular spacers 12, which may snugly fit within the bore and be of any suitable material. This roller is of similar shape to that of the shorter roller of Fig. 2 and similarly covered with rubber.

I am aware that prior to my invention, many other types of rollers were employed in the art of photography, but long periods of use with these other types have led me

to perfect one with the idea in view to eliminate the wrist strains already referred to, and to remove the possibility of injury to the prints in rolling, therefore, I do not broadly claim a new pressure-roller, but only to the extent that I have benefited the arts.

What I claim as new and desire to secure by Letters Patent of the United States, is 10 the following:

1. An article of manufacture, comprising, in combination, a framing and a roller, said framing composed of two pairs of arms cast integral and radiating from a common 15 center and a shaft, one pair of said arms forming a handle, and the other pair forming a wide-mouthed gap for the reception of said roller, and the said shaft adapted to carry the roller and be supported in the extremities of the arms forming the said gap, the surface of the roller being provided with tapered ends adapted to eliminate the edge-lines of the roller when in operation.
2. In a hand-roller device, a one-piece 25 frame of spider construction composed of two pairs of arms radiating from a common center, one pair of said arms being in

a plane and having its extremities turned downward forming a wide gap to receive said roller, the other pair of arms being in 30 a plane at right-angles to the former plane and having its extremities turned upwards and terminating in a cross-member forming thereby a handle to operate the device.

3. An article of manufacture, comprising, 35 in combination, a framing and a roller, said framing composed of two pairs of arms cast integral with each other and radiating from a common center, the ends of each pair of said arms turning outwards in opposed 40 directions and adapted thereby to form supports for a handle and a roller respectively, and which shall be approximately at right angles to each other and rigidly held so.

4. In a hand-roller device, a roller in the 45 form of a rod having a longitudinal bore for the reception of a shaft, and having its outside surface grooved and at the region of its ends tapered for reception of a rubber sleeve, the said groove and tapered ends 50 adapted to engage the sleeve and hold the same in position on said roller.

RALPH B. BIRD.
